UNITED STATES PATENT OFFICE.

NAPOLEON CARON, OF NASHUA, NEW HAMPSHIRE, ASSIGNOR TO NASHUA MANUFACTURING COMPANY, OF NASHUA, NEW HAMPSHIRE, A CORPORATION OF NEW HAMPSHIRE.

WEFT-REPLENISHING LOOM.

Application filed August 3, 1921. Serial No. 489,450.

To all whom it may concern:

Be it known that I, NAPOLEON CARON, a citizen of the United States, residing at Nashua, in the county of Hillsborough and 5 State of New Hampshire, have invented certain new and useful Improvements in Weft-Replenishing Looms, of which the following is a specification.

This invention relates to weft replenishing looms and will be herein disclosed as embodied in a loom having weft replenishing mechanism which comprises a multi-color magazine with separate compartments from which the bobbins or other weft carriers (hereinafter referred to as bobbins) are selectively released and dropped into the throat of the magazine preparatory to being transferred. It will be understood, however, that while the mechanism provided by the present invention is of particular utility in looms of this character, it is not limited in its application to such looms.

The magazines of these multi-color looms, 25 as heretofore constructed, have included a device mounted in the throat of the magazine to support and hold the selected bobbin yieldingly in the path of a transferer or hammer which is operated an instant after the release of the bobbin to force it into the active or running shuttle. If for any reason, such as a misplaced shuttle, the bobbin is not transferred, it then becomes necessary to remove this bobbin from the 30 throat of the magazine, since otherwise another bobbin will be released on the next pick and two bobbins thus will be present together in the magazine throat. If the transfer takes place under these conditions 35 some of the parts, usually the shuttle or the magazine throat, will be broken.

The mechanisms heretofore provided for the release of bobbins which fail to transfer have been open to the objection that 45 they are relatively complicated and very liable to get out of order. Usually there is no indication that anything is wrong until a smash occurs. A further difficulty encountered in the use of these prior constructions is that occasionally a complete transfer of the bobbin will not be made but, instead, the bobbin will be only partially forced into the running shuttle, and when the lay starts to move forward it will

crowd the bobbin against some part of the 55 magazine throat and break either the shuttle or the throat piece.

The present invention is particularly concerned with the means for retaining the bobbin which has been released in the 60 throat of the magazine in position for transfer into the running shuttle, and with the arrangement for getting rid of this bobbin in case it is not transferred. It is the chief object of the invention to devise 65 a construction which will overcome the difficulties experienced in using prior arrangements. Stated more specifically, the invention aims to devise a mechanism of this character which will be very simple in construction, will require practically no care or attention, and will be absolutely reliable in operation.

The nature of the invention will be readily understood from the following description when read in connection with the accompanying drawings, and the novel features will be particularly pointed out in the appended claims.

Referring now to the drawings, 80 Figure 1 is a side elevation of the magazine and certain associated parts of a well known automatic weft replenishing loom equipped with mechanism embodying the present invention, certain of the parts, 85 however, being shown in cross section;

Fig. 2 is a perspective view of the parts in the throat of the magazine, showing the transferer and a bobbin in position to be transferred;

Fig. 3 is a perspective view of the parts shown in Fig. 1, but showing them in the positions occupied immediately before the transferring operation is effected; and

Figs. 4, 5 and 6 are perspective views of details provided by this invention.

The drawings show the invention as applied to the well known Crompton and Knowles loom, the particular loom shown being that designed especially for weaving blankets. This construction comprises a magazine 2 having four compartments for retaining full bobbins of different colors. Four shuttles, each carrying a different color, are used in this loom and an automatic pattern mechanism controls the selection of the shuttles. An automatic weft replenishing mechanism cooperates with

this pattern mechanism to select a bobbin of the proper color and release it from its compartment when the weft in the running shuttle reaches a point of critical exhaustion or becomes entirely spent. The bobbin so released drops into the throat of the magazine where it is retained temporarily until the shuttle is boxed on the magazine side of the loom in position for the bobbin changing or weft replenishing operation to be completed.

Inasmuch as the construction and operation of this loom is well understood by those skilled in this art, no detailed description of it is necessary here. The drawings, however, show the usual hammer or transferer 3 formed on the outer end of a transferer lever 4 which is pivoted at 5 and is connected in the usual manner with a bunter lever 6 arranged to be operated by a bunter 7 carried by the lay 8. The drawings also show the shuttle feeler 9 which is mounted and operated in the usual manner. These devices all form parts of the automatic weft replenishing mechanism and they are all shown in Fig. 1 in their normal positions, the transferer 3 and the feeler 9 both being in their raised or inoperative positions.

When a spare bobbin is released from one of the magazine compartments, as above described, it drops into the position occupied by the bobbin B, Fig. 2. The tip of the bobbin rests on two fieldingly mounted plates 12 and 13, respectively, Fig. 2, with which these magazines regularly are equipped while the head of the bobbin is supported partly on a flange or abutment 14 formed on the magazine wall, and partly by a supporting device 15 which is constructed in accordance with the present invention. This device, as best shown in Fig. 4, has an upright part provided with a hole 16 to receive a bolt 17 by means of which this device is pivotally mounted on a portion of the magazine. A pin 18 projects rigidly from one side of this device while an arm projects from the opposite side thereof and is provided with a lip 19 on which the head of the bobbin B rests. This lip is separated from the body 15 by a notch 20 which is cut out to avoid interference with the lower part 21 of the magazine wall. It will be observed that this wall 21 is provided with a flange or abutment 22 similar to the part 14, these parts cooperating to guide the head of the bobbin into the proper position to be transferred.

Normally this bobbin supporting device 15 is retained by gravity in substantially its operative position, in which it is shown in Figs. 1, 2 and 3. The contact between this member and the lower edge of the flange 22, Fig. 2, prevent the part 15 from swinging further toward the abutment 14 but it is entirely free to swing in the opposite direc-

tion. Consequently, so long as the parts remain in this condition, the support 15 offers no substantial resistance to the movement of a bobbin through the throat of the magazine; and if a bobbin were placed in the position indicated at B, Fig. 2, the weight of the bobbin head would be ample to swing the supporting device in a clockwise direction, Fig. 1, and thus allow the bobbin to drop freely through the magazine throat. This action is desirable at all times except when the weft replenishing or bobbin changing operations are being performed. At this time, however, it is necessary to prevent this movement in order to enable the supporting device 15 to retain the bobbin in the throat of the magazine until the transferer 3 forces it into the shuttle 24. For this purpose a stop plate 25 is secured rigidly to the shuttle feeler lever 26 by a bolt 27. This stop device as best shown in Figs. 3 and 6, has what may be described as a Z-shape, and it comprises a shank 28 that is slotted to receive a lug on the rear side of the lever 26 and also to receive the bolt 27, an intermediate portion that extends substantially at right angles to the shank 28, and an end part 29 projecting forward substantially parallel with the shank 28.

When the weft replenishing or bobbin changing operation is initiated by the automatic mechanism with which these machines are provided, the feeler 9 is dropped from its normal position, as shown in Fig. 1, into its operative position as shown in Fig. 3, the stop 25 moving with it and the forward edge of this stop moves down behind the pin 28 which projects rigidly from the bobbin supporting device 15. This relationship of the parts is clearly shown in Fig. 3. Substantially simultaneously with this movement, a bobbin is released from one of the compartments in the magazine and drops into the throat, as shown at B, Fig. 2. Since the bobbin supporting device 15 is locked in its operative position at this time by the stop 25, the bobbin will be held firmly in this position until the transferer 3 is operated upon the next beat up of the lay 8. The transferer then will force this bobbin through the throat of the magazine and into the running shuttle, thus driving out the spent bobbin. If, however, the shuttle should not be properly boxed, as for instance if it should rebound so that the transfer could not be made successfully, the contact of the shuttle with the feeler 9 would prevent the transfer. The shuttle would be shot out of the box again, and the shuttle feeler would be returned immediately to its upper position, thus unlocking the bobbin holding device 15 and permitting it to swing backwardly to release the bobbin B. This bobbin, therefore, will immediately drop through the throat of the magazine by grav-

ity. The weft in the running shuttle still being exhausted, the automatic detecting mechanism will again operate in the manner just described to release another bobbin and to drop the feeler 9 into its operative position again. If the shuttle is properly boxed on the next pick the transfer will be completed; but if the transfer cannot be made at this time the operations above described will be repeated until the transfer is successfully made. Each of the bobbins which fail to transfer will, however, drop through the throat of the magazine before another bobbin is released so that two bobbins will never be present in the magazine throat.

It will be observed that when the transfer 3 drives the bobbin B through the magazine throat, the lip 19 must move back very slightly to permit the head of the bobbin to pass between it and the rigid abutment 14. This very slight yielding movement is permitted by the resiliency of the stop 25. That is, the intermediate part of this stop between the shank 28 and head 29 can spring slightly to enable the part 15 to yield sufficiently for this purpose.

It will now be appreciated that the parts 25 and 15 added by this invention are of very simple construction and that they perform completely the operations heretofore performed by a relatively complicated mechanism. The supporting device 15 is always free to move upon engagement therewith of a bobbin to permit the bobbin to pass freely through the throat of the magazine, except during the time that the bobbin changing operation is being performed, and during this time it is held in its operative position by the stop 25. The construction is so simple that it requires practically no attention and any possibility of its getting out of order is substantially eliminated. It has proved in practice to be extraordinary reliable.

In case a bobbin should be only partially transferred, leaving a portion of the bobbin head projecting above the shuttle, this projecting part will strike the lip 19 of the supporting device when the lay swings backward, but no damage will be done because the supporting device will, at this time, be unlocked so that it can swing backward freely until it clears the misplaced bobbin. Any damage to the magazine throat or the shuttle due to such an occurrence, therefore, is avoided. It should be noted that the lower part of the edge of the stop 28 is rounded or bevelled so that if the supporting device should fail for any reason to return to its normal position after it had been swung away from such position, the contact of this part of the stop with the pin 18 will return the supporting device to its operative position.

It will be observed that there is consider-

able space between the bottom of the forward side of the magazine,—that is, the side toward the breast beam,—and the upper edge of the shuttle 24. (See Fig. 1). According to the present invention the greater part of this space is filled by a shuttle positioning device 31. This part is secured to the lower side of the abutment or flange 14 by means of a bolt 32 which passes through the holes 33 and it is steadied by a pin that projects into the hole 34. This part is made in the form of a U with one leg secured to the lower side of the magazine and the open end pointing forward away from the shuttle. It frequently happens that the shuttle, when it boxes on the magazine side of the loom, is misplaced vertically in the shuttle box. As the lay beats up, a shuttle so misplaced will strike the rounded rear end of the part 31 and be forced thereby down into the box.

This rear end of the part 31 also acts as guide for the head of the bobbin while it is being transferred and effectually prevents any tendency of the bobbin to fly out laterally between the bottom of the magazine and the top of the shuttle box. Furthermore, since the lower edge of this part presents a solid surface for contact with the shuttle, there is no possibility of the shuttle catching on it and being broken when the lay starts on its backward beat.

While I have herein shown and described the best embodiment of the invention of which I am at present aware, it will be understood that this embodiment may be modified in minor particulars without departing from the spirit or scope of this invention. This application is a continuation of my co-pending application Serial No. 419,840 filed October 26, 1920 so far as the subject matter common to the two applications is concerned.

Having thus described my invention, what I desire to claim as new is:

1. In an automatic weft replenishing loom, the combination of a magazine for spare bobbins, said magazine having a throat through which said bobbins are discharged into the running shuttle, and a bobbin supporting device mounted in said throat and normally moveable freely upon engagement therewith of a bobbin to permit the bobbin to drop through the throat due to its own weight.

2. In an automatic weft replenishing loom, the combination of a magazine for spare bobbins, said magazine having a throat through which said bobbins are discharged into the running shuttle, a bobbin supporting device mounted in said throat and normally moveable freely upon engagement therewith of a bobbin to permit the bobbin to drop through the throat, and means operated by the weft replenishing mechanism for preventing such movement of said device.

- and holding it in its operative position while the weft replenishing operation is being performed.
3. In an automatic weft replenishing loom, 5 the combination of a magazine for spare bobbins, said magazine having a throat through which said bobbins are discharged into the running shuttle, a bobbin supporting device mounted in said throat and normally movable freely upon engagement therewith of a bobbin to permit the bobbin to drop through the throat, and means for holding said device against such movement while the weft replenishing operation is being performed, but permitting such movement again immediately after said operation has been completed.
4. In an automatic weft replenishing loom, 20 the combination of a magazine for spare bobbins, said magazine having a throat through which said bobbins are discharged into the running shuttle, a supporting device for holding a bobbin in said throat, said device being normally inoperative to support 25 a bobbin in said throat, and means operated by the weft replenishing mechanism for holding said device in its operative position to enable the bobbin changing operation to be performed.
5. In an automatic weft replenishing loom, 30 the combination of a magazine for spare bobbins, said magazine having a throat through which said bobbins are discharged into the running shuttle, a bobbin supporting device mounted in said throat and normally inoperative to support a bobbin in said 35 throat, and means operated by the weft replenishing mechanism for rendering said device operative to enable the bobbin changing operation to be performed.
6. In an automatic weft replenishing loom, 40 having a shuttle feeler, the combination of a magazine for spare bobbins, said magazine having a throat through which said bobbins are discharged into the running shuttle, a bobbin supporting device mounted in said throat and normally movable freely upon engagement therewith of a bobbin to permit the bobbin to drop through the throat, and means for locking said device against such movement 45 during the weft replenishing operation only.
7. In an automatic weft replenishing loom, 45 having a shuttle feeler, the combination of a magazine for spare bobbins, said magazine having a throat through which said bobbins are discharged into the running shuttle, a bobbin supporting device mounted in said throat and normally movable freely upon engagement therewith of a bobbin to permit the bobbin to drop through the throat, and 50 a part connected with the shuttle feeler for locking said device in its operative position while the feeler is in its operative position.
8. In an automatic weft replenishing loom, 55 the combination of a magazine for spare bobbins, said magazine having a throat through which said bobbins are discharged into the running shuttle, a bobbin supporting device mounted in said throat and normally held yieldingly in said position, and means arranged to be operated by the weft replenishing mechanism for locking said device in said position while a bobbin is being transferred.
9. In an automatic weft replenishing loom, 60 having a shuttle feeler, the combination of a magazine for spare bobbins, said magazine having a throat through which said bobbins are discharged into the running shuttle, a pivoted bobbin supporting device normally retained by gravity in substantially its operative position in said throat but movable freely upon the engagement therewith of a bobbin to permit the bobbin to drop through the throat, and a stop secured to the shuttle feeler and operative to engage a part rigid 70 with said device to prevent such movement while the weft replenishing operation is being performed.
10. In an automatic weft replenishing loom, 75 having a shuttle feeler, the combination of a magazine for spare bobbins, said magazine having a throat through which said bobbins are discharged into the running shuttle, a bobbin supporting device mounted in said throat and normally inoperative to support a bobbin in said 80 throat, and means operated by the weft replenishing mechanism for rendering said device operative to enable the bobbin changing operation to be performed.
11. In an automatic weft replenishing loom, 85 having a shuttle feeler, the combination of a magazine for spare bobbins, said magazine having a throat through which said bobbins are discharged into the running shuttle, a bobbin supporting device pivoted on a portion of said magazine and having a part normally held by gravity in said throat in position to engage the head of a bobbin and retain it in said throat, said device being normally free to move when so engaged by a bobbin to permit the bobbin to drop through the throat and having a pin projecting laterally therefrom, and a stop secured to the shuttle feeler in position to engage said pin when the feeler is moved 90 into its operative position and operative to prevent the backward movement of said device so long as the feeler remains in said position.

NAPOLEON CARON.
